UNITED STATES PATENT OFFICE.

CLARA S. DAVIS, OF DETROIT, MICHIGAN.

NEEDLE AND PIN CUSHION ATTACHMENT FOR SEWING-MACHINES.

1,231,503.

Specification of Letters Patent. Patented June 26, 1917.

Application filed February 16, 1917. Serial No. 149,026.

To all whom it may concern:

Be it known that I, CLARA S. DAVIS, a citizen of the United States, and resident of Detroit, in the county of Wayne and

5 State of Michigan, have invented certain new and useful Improvements in Needle and Pin Cushion Attachments for Sewing-Machines, of which the following is a specification.

10 The present invention has reference, generally, to sewing machines; and, the invention relates, more particularly, to an improved needle and pin cushion therefor.

15 The invention has for its dominant object to provide a novel needle and pin cushion adapted for arrangement over the arm of a sewing machine frame, whereby, needles or pins as used during the sewing operation may be placed therein or removed there-

20 from.

It is also an object of the invention to provide a needle and pin cushion having a flexible securing means, whereby, the same may be securely engaged over the arms of 25 practically all types of sewing machines and also, may be easily removed therefrom when it is desired.

Among other aims and objects of the invention may be recited, the provision of a 30 device of the character mentioned with a view to compactness, and in which the number of parts are few, the construction simple, the cost of production small, and efficiency and operation high.

35 The improvements in the detail and arrangement of parts will be apparent from an inspection of the accompanying drawing, in connection with the specific description hereinafter contained, and wherein the preferred embodiment of the invention is disclosed for the purpose of imparting a full understanding of the same.

In the drawings:

40 Figure 1 is a side elevation of my improved needle and pin cushion as applied to the arm of a sewing machine frame, and

Fig. 2 is a top plan of the same.

45 Referring more specifically to the drawings, wherein like reference numerals designate corresponding parts throughout the several views, it is to be noted that I have shown by way of illustration, my improved needle and pin cushion as applied to the arm of a sewing machine frame, designated in 50 its entirety by the numeral 1, the said cushion comprising a tapered flexible band 2,

preferably formed of fabric or other suitable material and having the ends thereof curved inwardly to permit the same to properly conform to the shape of the sewing machine arm when applied thereto. A plurality of eyelets, generally indicated by the numeral 3, are arranged within the opposite side portions of the flexible band 2 and are adapted to receive therethrough, suitable lacing indicated by the numeral 4, whereby the free ends of the band may be connected and the same thus, securely engaged about the sewing machine arm.

55 Upon one face of the flexible band 2, there is arranged a plurality of elongated pockets 4', the said pockets being formed by stitching strips of fabric to the band 2 as at 5. Within the elongated pockets 4', suitable packing such as hair, raw cotton, saw dust 60 or the like may be arranged and the opened ends thereof then closed by continuing the stitching about the adjacent ends of the said strips. By so packing the pockets 4', it will be understood that a plurality of pin or 65 needle cushions are provided, into which the pin or needle as used in the sewing operation may be placed or removed.

70 It is to be noted, that by arranging the elongated pocket or pin cushion upon the flexible band 2 in proximity to the opposite side portions thereof, the same when applied to the arm of the sewing machine frame will be so arranged as to permit the insertion and removal of needles or pins with but little 75 effort, and further, by reason of their convenient positioning, will maintain the needles or pins in positions as to permit the same to be withdrawn therefrom and engaged with the material during the sewing 80 operation or vice versa. It is to be also understood, that the improved cushion, by reason of the flexible band 2 into which the same is secured, may be applied to practically 85 all types of sewing machines, and when 90 in position thereon will not in any way interfere with the sewing operation.

95 Obviously, the construction shown is capable of considerable modification, and such modification as is within the scope of the appended claims, I consider within the spirit 100 of my invention.

I claim:

105 1. A needle and pin cushion for sewing machines, comprising a flexible supporting band formed of fabric adapted for arrangement about the arm of the sewing machine

frame, said band having a series of eyelets arranged in the opposite side portions thereof, lacing engageable with said eyelets for connecting the free ends of the band, and 5 pin cushions secured to portions of the band.

2. A needle and pin cushion for sewing machines, comprising a flexible supporting band formed of fabric adapted for arrangement about the arm of the sewing machine frame, 10 said band having a series of eyelets arranged adjacent the opposite side portions thereof, lacing engageable with said eyelets for adjustably connecting the free ends of the band, and a pair of elongated pin cushions 15 secured to said band adjacent the side portions of the same.

3. A needle and pin cushion for sewing

machines, comprising a flexible supporting band adapted for arrangement about the arm of the sewing machine frame, the opposite extremities of said band being curved inwardly to permit the same to conform to the shape of the sewing machine frame arm and having a plurality of eyelets arranged in the opposite side portions thereof, lacing 20 engageable with said eyelets for adjustably connecting the free ends of the band, and a plurality of longitudinally disposed pin cushions secured to the band in proximity of the opposite side portions thereof. 25

In testimony whereof, I affix my signature hereto.

CLARA S. DAVIS.
